CLAIM

The ornamental design for an electronic device, as shown and described.

DESCRIPTION

FIG. 1 is a bottom front perspective view of an electronic device showing the claimed design.

FIG. 2 is a bottom rear perspective view thereof;

FIG. 3 is a front view thereof;

FIG. 4 is a rear view thereof;

FIG. 5 is a top view thereof;

FIG. 6 is a bottom view thereof;

(Continued)

FIG. 7 is a left side view thereof; and,
 FIG. 8 is a right side view thereof.
 The broken lines in the figures show portions of the electronic device that form no part of the claimed design.

1 Claim, 2 Drawing Sheets
